Patented Oct. 25, 1921.

UNITED STATES PATENT OFFICE.

STANISLAW J. KORKOSZ, OF SCHENECTADY, NEW YORK.

VISE.

1,394,912.

Specification of Letters Patent.

Patented Oct. 25, 1921.

Application filed July 1, 1919. Serial No. 307,940.

To all whom it may concern:

Be it known that I, STANISLAW J. Korkosz, a citizen of the United States, residing at Schenectady, in the county of Schenectady, State of New York, have invented certain new and useful Improvements in Vises, of which the following is a specification.

The present invention relates to vises such for example, as are used by tool-makers and has for its primary object to provide an improved structure and arrangement in a vise whereby the same is universally adjustable and at the same time is compact and well supported.

15 A further object of my invention is to provide a universally adjustable vise which can be adjusted with great accuracy and can be clamped in any adjusted position.

For a consideration of what I believe to be novel and my invention, attention is directed to the accompanying specification and the claims appended thereto.

In the drawing, Figure 1 is a side elevation partly in section of a vise embodying my invention; Fig. 2 is a top plan view thereof; Fig. 3 is an end view partly in section; Fig. 4 is a section taken on line 4-4, Fig. 3; Fig. 5 is a detail view taken on line 5-5, Fig. 3 and Fig. 6 is a detail sectional view, taken on line 6-6, Fig. 4.

The vise comprises four parts or members designated on the drawing, A, B, C and D. The two parts or members A and B are adjustably connected together by an arcuate dovetailed connection to form what may be termed the upper half of the vise, the dovetailed connection being such as to permit members A and B to be adjusted in a vertical plane relatively to each other. The two parts or members C and D are similarly connected together by an arcuate dovetailed connection to form what may be termed the lower half of the vise, members C and D likewise being adjustable relatively to each other in a vertical plane, which plane may be at an angle to the plane in which members A and B are adjustable. The upper and lower halves of the vise are then connected together in a horizontal plane in such manner that they may be turned in such plane relatively to each other. By this arrangement, as will appear more clearly herein-after, the jaws of the vise which are carried by member A may be adjusted to any desired

angle relatively to member D which is the 55 part of the vise which is fixed to the work bench or other support.

The member A comprises a block in the form of a longitudinal section of a cylinder having a flat top surface 10 and rounded side 11. In the ends of member A are undercut grooves 12 which form part of the dovetail connection with member B. In the upper surface 10 of member A is a longitudinally extending inverted T-shaped slot 13 65 at the center of which is a cross piece 14. Located in slot 13 is a rod 15 which is supported at its central portion in cross piece 14 and is provided with right hand and left hand threads on which screw T-shaped nuts 70 16 which fit slots 13 and are fastened to the jaws 18 of the vise by bolts 19. Vise jaws 18 are of the width of surface 10 and slide on such surface. On one end of rod 15 is a head 15^a shaped to receive a tool for turning 75 the rod and, as is obvious, by turning rod 15, jaws 18 of the vise may be moved toward and away from each other, nuts 16 traveling back and forth on the threads of rod 15 and moving jaws 18 with them. Jaws 18 are 80 provided adjacent their ends with tongues 20 which are located in longitudinally extending grooves 21 in the surface 10 of member A thereby providing guides for jaws 18 and also a means to prevent them from turn- 85 ing.

The member B comprises a block having a concave top surface to form a cradle in which member A rests and a flat bottom surface. The curvature of the top surface of 90 member B is indicated by line b in Fig. 3 and the upper side edge of member B is indicated by line b' in Fig. 1. The side surfaces of member B may be sloping as shown in Fig. 3. At the two ends of member B are 95 flanges 22 and 23 which are undercut to form tongues 24 and 25 which fit into grooves 12. Flange 22 is preferably formed integral with the body part of member B while flange 23 is carried by an end plate 26 which is fastened to the body part of member B by bolts 27. As shown in Fig. 5 the arrangement is such that when bolts 27 are screwed up to clamp tongues 24 and 25 into grooves 12, a slight clearance is left between end plate 26 100 and the body part of member B as indicated at 28. By this arrangement it is assured that members A and B can be firmly clamped 105

together. To adjust members A and B angularly relatively to each other, bolts 27 are first loosened after which member A is rocked on member B through the desired 5 angle and then clamped together again by tightening bolts 27.

The members C and D are of the same general contour as are members A and B respectively and are fastened together in the 10 same general manner. Member C has a flat top surface 30 and convex side surface 31 and is provided at its two ends with undercut grooves 32. Member D has a concave top surface which forms a cradle in which 15 member C rests and on which it can be turned through an arc of a circle. The upper edge of the side wall of member D is indicated by the line d in Fig. 3. Its bottom surface is flat adapting it to rest on a bench 20 or other support and it is provided on its ends with ears 33 and at its sides with suitable recesses 34 to receive bolts for fastening it to a bench. Member D is provided 25 with flanges 35 and 36 which are undercut to provide tongues 37 and 38 for engagement in grooves 32. Flange 35 is formed integral with the body portion of member D while flange 36 is carried by an end plate 39 which is fastened to the body portion of 30 member D by bolts 40. By tightening bolts 40 the members C and D can be clamped firmly together and they may be adjusted 35 relatively to each other in the same manner as members A and B.

35 The bottom flat surface of member B rests on the upper flat surface of member C and the two are fastened together in such manner as to permit of their adjustment relatively to each other in a horizontal plane. 40 To this end the member C is provided with an annular recess 42 in which is fastened a ring 43 having an undercut inner edge as indicated at 44, Fig. 1. Ring 43 is fastened in place by suitable studs 45 as shown in Fig. 45 6, such studs being inserted from below through slots 46 in the sides of member C, the heads of studs 45 being located in such slots. Depending from the bottom of member B is a projection 47 which is located in 50 recess 42 and held therein by ring 43, the beveled edge 44 of which fits over a complementary beveled edge on projection 47. When studs 45 are loosened it will be clear 55 that the upper half of vise comprising members A and B may be turned in a horizontal plane relatively to the lower half of the vise comprising members C and D, and after being adjusted the two halves may be firmly clamped together by tightening studs 45 60 thus pulling ring 43 down into firm engagement with the beveled edge of projection 47.

In connection with a vise as above described, particularly when intended for accurate work, it is usually desirable to 65 provide suitable scales for indicating the ad-

justments of the respective members relatively to each other, and in the drawing a scale 50 laid out in degrees and minutes is provided for indicating the adjustment between members C and D, and a similar scale, 70 (not shown) may be provided between members B and C. In the case of members A and B I provide member A with teeth 52 which extend around its outer curved surface and with which meshes a worm 53 on one 75 end of a rod 54. By turning rod 54 member A will be adjusted relatively to member B. Rod 54 is located in an opening in projection 47, (Fig. 4) and has a knob 55 on its outer end by means of which the rod is 80 turned. On knob 55 is marked a scale to show seconds of adjustment and between members A and B is a scale 56 which shows minutes and degrees of angular adjustments. Members A and B can be adjusted relatively 85 to each other therefore as to degrees, minutes and seconds.

The operation and manner of using my improved vise is obvious from the foregoing description. When in what may be termed 90 the zero or normal position, the zero mark of scale 50 is at the indicating point 50^a on member D; the zero mark of scale 56 is at the indicating point 56^a on member B, and the upper half of the vise is so adjusted 95 relatively to the lower half that the vertical planes of adjustment between members A and B and between members C and D lie at right angles to each other. The face of the vise which is the surface 10 of member A is 100 then horizontal. A piece upon which work is to be performed may be clamped between jaws 18 and it may be then adjusted and clamped at the desired angle by adjusting members A, B, C and D relatively to each other and clamping them in such adjusted 105 positions.

In accordance with the provisions of the patent statutes, I have described the principle of operation of my invention, together 110 with the apparatus which I now consider to represent the best embodiment thereof, but I desire to have it understood that the apparatus shown is only illustrative and that the invention can be carried out by other 115 means.

What I claim as new and desire to secure by Letters Patent of the United States, is:—

1. A vise comprising upper and lower halves which are fastened to each other and 120 arranged for adjustment in a horizontal plane, and clamping elements carried by the upper half which are adjustable toward and away from each other, said upper half comprising two members having curved engaging surfaces which are adapted to stand in one plane and said lower half comprising two members having curved engaging surfaces which are adapted to stand in a plane at an angle to the first named plane 125 130

whereby said clamping elements can be adjusted in a horizontal plane and in either of two vertical planes.

2. A vise comprising a member adapted 5 to be fastened to a support and having a curved upper surface, a second member having a curved lower surface which fits the curved upper surface of said first member, said second member having a flat

10 upper surface, a third member having a flat lower surface which rests on said second member and a curved upper surface, a fourth member having a curved lower surface which fits the curved upper surface 15 of said third member, clamping jaws carried by said fourth member, an object held in said jaws being adjustable in a horizontal plane or in either of two vertical planes, and means for clamping said members in 20 adjusted positions.

3. A vise comprising upper and lower halves which are fastened to each other and arranged for adjustment in a horizontal plane relatively to each other, each of said 25 halves comprising two members which are joined together by arcuate tongue and groove connections whereby they may be adjusted in a single vertical plane relatively to each other, said horizontal adjustment permitting the two planes in which the members of the respective halves are adjustable to be located at various angles relatively to each other.

4. A vise comprising upper and lower 35 halves which are fastened to each other and arranged for adjustment in a horizontal plane relatively to each other, each of said halves comprising two members which are joined together by arcuate tongue and 40 groove connections whereby they may be

adjusted in a single vertical plane relatively to each other, said horizontal adjustment permitting the two planes in which the members of the respective halves are adjustable to be located at various angles 45 relatively to each other, and means for clamping said halves and members in adjusted positions.

5. A vise comprising upper and lower halves having engaging faces, one of said 50 halves having a recess in such face, a projection carried by the other half which is located in said recess, said projection having a beveled edge, a ring in said recess which engages said beveled edge, means for clamping said ring to the one half to fasten said 55 two halves together, each of said halves being formed of two members which members are angularly adjustable relatively to each other, and clamping elements carried by one 60 of the members of the upper half which are adjustable toward and away from each other.

6. A vise comprising upper and lower halves having engaging faces, one of said 65 halves having a recess in such face, a projection carried by the other half which is located in said recess, said projection having a beveled edge, a ring in said recess which engages said beveled edge, means for clamping said ring to the one half to fasten said 70 two halves together, each of said halves being formed of two members, which members are angularly adjustable relatively to each other, the means of adjustment between two 75 of said members comprising a worm and gear teeth.

In witness whereof, I have hereunto set my hand this 30th day of June, 1919.

STANISLAW J. KORKOSZ.
